UNITED STATES PATENT OFFICE

EMMET H. MORROW, OF CHICAGO, ILLINOIS, ASSIGNOR OF ONE-HALF TO JOHN C. MORROW, OF CHICAGO, ILLINOIS

HIGH PRESSURE OILER

Application filed October 21, 1929. Serial No. 401,291.

This invention relates to a high pressure oiler, and particularly to an oil can arranged to eject oil under high pressure.

An object of the invention is to provide an oil can whereby oil may be ejected therefrom under high pressure.

Another object of the invention is to provide an oil can having a cylinder arranged therein with a piston movable in said cylinder for trapping a charge of oil and ejecting said charge under pressure.

Another object of the invention is to provide an oil can wherein oil may be ejected under pressure irrespective of the position of the oil can.

A still further object of the invention is to provide an oil can having a spout which is formed with a cylindrical portion and with a tapered portion there being a piston in the cylindrical portion for entrapping a charge of oil on one stroke of the plunger and ejecting said charge on the next stroke of the plunger.

A still further object of the invention is to provide a high pressure oil can which is economical to manufacture and efficient and positive in use.

The above, other and further objects of the invention will be apparent from the following description, accompanying drawings, and appended claims.

According to the invention an oil can spout is formed with a cylindrical portion and a tapering portion with a piston in the cylindrical portion which piston is movable by means of a plunger having an end which projects through the oil can. Suitable valves are arranged so that the piston will on one movement of the plunger entrap a charge of oil in the cylinder and on the subsequent movement discharge said charge under pressure and receive a second charge.

Embodiments of the invention are illustrated in the accompanying drawings and the views thereof are as follows:

Figure 1 is a vertical central section through an oil can and a spout with a part of the spout shown in elevation containing one embodiment of the invention.

Figure 2 is a fragmental side elevational

view of the arrangement of Figure 1 showing the plunger at the inner end of its stroke and the relation of the piston to the discharge end of the cylindrical portion of the spout.

Figure 3 is an enlarged elevational view of a spring arranged within the cylindrical portion of the spout.

Figure 4 is an enlarged section taken on line IV—IV of Figure 1.

Figure 5 is a fragmental elevational view partially in section of an oil can showing a modified form of piston.

Figure 6 is a view similar to Figure 5 showing still another form of piston.

Figure 7 is a section taken on line VII—VII of Figure 5.

Figure 8 is an enlarged section taken on line VIII—VIII of Figure 5.

Figure 9 is an enlarged section taken on line IX—IX of Figure 6.

Figure 10 is an enlarged section taken on line X—X of Figure 6.

An oil can 1 is provided with an open end 2 which is threaded and a recessed bottom 3 which bottom is secured to the can 1 by having the lower margin of the can body crimped over as at 4 the lower margin of the member forming the recessed bottom 3.

A hollow sleeve 5 is fastened in a centrally disposed recess 6 in the bottom 3 by having its flanged end 7 soldered or welded to the bottom 3. The upper end of the sleeve 5 terminates below the open end 2 of the can and is provided with a gasket 8 about the upper end of the sleeve 5.

A plunger 9 is slidably arranged in the sleeve 5 and has its outer end extending outwardly of the depressed bottom 3 of the can where it is provided with a head 10 which serves to move the plunger whenever oil is to be discharged from the can. A spring 11 is interposed between the outer surface of the depressed bottom 3 and the head 10 of the plunger so as to maintain the plunger normally in outward position, that is in the position shown in Figures 1, 5, and 6 of the drawings.

The upper end of the plunger 9 is reduced in diameter and threaded at 12. A plunger valve 13 having a threaded interior is

threaded onto the reduced end 12 of the plunger. The valve shown in Figures 1 and 2 has an enlarged head 14.

The spout comprises a cap 15 having threads for engaging the threaded end 2 of the can 1. Above the cap 15 the spout is formed for a portion of its length as a cylinder 16 and then the spout tapers forming a tapered portion 17 to the end. The cylindrical portion 16 and the tapered portion 17 are integral being formed from the same material. The walls of the spout connecting the cylindrical portion 16 and the tapered portion 17 form an inner annular shoulder 18. 10

15 A gasket 19 is arranged within the cap 15 for making a leak tight joint with the open end 2 of the can.

The upper end of the sleeve 5 terminates a short distance below the open end 2 of the can so that when the parts are in normal position the head 14 of the plunger valve 13 is disposed near the end 2 of the can. 20

A cage member 20 comprising a circular cage formed from sheet metal and having a flared skirt 21 is provided with a transverse member 22 having a central aperture 23 therein which aperture serves as a valve seat. The member 22 is pressed into the cage 20 so as to be held firmly in the same. A ball valve 24 is interposed in the cage between the upper end thereof and the transverse member 22 and is held in engagement with the valve seat 23 by means of a spring 25. The side portions of the cage 20 are apertured at 26 to afford means for discharging oil through the cage 20. The upper end of the cage member 20 is imperforate. 25

A piston is arranged within the cylindrical portion 16 of the spout. The piston illustrated in Figures 1 and 2 comprises a counter bored member 27 having a central aperture 28 in its lower end and with the walls of the lower end outwardly of said aperture countersunk at 29 to receive the head 14 of the plunger valve 13. The shape of the head 14 and the countersunk end 29 of the piston is such as to afford a leak tight seal between these parts when in normal position. 40

50 A spring 30 is arranged between the transverse member 22 of the cage 20 and the lower end of the counter bored portion of the piston 27 for maintaining the piston normally away from the cage member 20 and in contact with the head 14 of the plunger valve 13. The spring 30 is formed with its ends 31 and 32 of larger diameter than the balance of the spring so as to allow passage of oil thereby when the piston 27 is operated in a manner to be hereinafter more fully explained. 55

Figure 1 shows the parts when in normal position and Figure 2 shows the parts when the plunger 9 is pressed to the outermost po-

sition of its stroke for discharging oil from the spout. 60

The operation of the form of the invention illustrated in Figures 1 to 4 inclusive is as follows:

The can 1 is supplied with oil by removing the cap 15 therefrom and filling the can whereupon the cap 15 is replaced. The piston 27 normally seats against the head 14 of the plunger valve 13 so as to seal passage 75 into the piston. The ball valve 24 normally closes the upper end of the cylindrical portion of the spout. The head 10 of the plunger 9 is then pressed inwardly to the position shown in Figure 2 and is then released. The spring 11 returns the plunger to normal position, that is the position shown in Figure 1 and the spring 30 tends to return the piston 27 to its normal position. Movement of the piston to the upper end of the cylindrical portion 16 of the stem creates a partial vacuum within the cylinder which tends to retard the movement of the piston 27 to normal position thereby separating the piston from its engagement with the head 14 of the plunger valve 13 and allowing oil to enter the cylindrical portion 16 of the spout. The oil will not pass the ball valve 24 at this time as the spring 25 immediately seats the ball when pressure on the plunger is released. By the time the piston 27 has reached its normal position such as that shown in Figure 1 a charge of oil will be entrapped within the cylindrical portion 16 of the spout and a subsequent movement of the plunger 9 will compress this charge of oil and force it outwardly past the ball valve 24 discharging the same laterally of the cage 20 through the aperture 26 and outwardly of the end of the spout under pressure. Release of pressure against the plunger will allow filling of the cylindrical portion 16 with another charge of oil provided the can is held downwardly so that the oil can flow into this portion as the piston 27 is slowly returning to normal position. 95

An oiling seal 33 having an arcuate end 34 may be applied to the discharge end of the spout for aiding in ejecting the oil under pressure from the spout to a fitting. The end 34 may be of rubber composition so as to effectively seal the connection between the end of the spout and its fitting thus aiding in discharging of the oil under pressure. 100

Provision of the ball valve 24 serves also as a means to prevent leakage and dripping from the end of the spout should the can be inadvertently overturned or held in upside down position. 110

Figure 2 shows that the spring 30 is not compressed to such an extent as to completely 115 clog or close oil passage through the counter bored portion of the piston 27. Furthermore, the provision of the oil discharge aperture 26 in the side of the cage member 20 eliminates clogging of passages by the compression 120

of the ball valve spring 25 which clogging is usual when the oil discharge opening is in alignment with the axis of the spring.

The form of the invention illustrated in Figure 5 is the same as that described with reference to Figures 1 to 4 with the exception of a modified form of piston and of its connection with the plunger.

A plunger 35 is arranged within the sleeve 5 and is provided outwardly of the recessed end 3 of the can with a head 10 and a spring 11. The upper end of the plunger 35 is provided with a button head 36 having a reduced neck 37 immediately under the head 36.

The piston illustrated in Figure 5 comprises a member having a counter bored larger end 37 and a smaller counter bored lower portion 38, the portions 37 and 38 being formed from a single piece of material such as brass or the like. The counter bore in the portion 38 is of smaller diameter than is the counter bore in the portion 37 and likewise the outer diameters of these two portions are different with the diameter of the portion 38 smaller. A seat 39 is formed within this member at the junction of the two counter bores within the same, and a ball valve 40 is normally held in this seat by means of a spring 41 which is retained against the ball 40 by means of a collar 42 pressed into the upper end of the counter bore of the portion 37. Lateral openings 43 are provided in the lower portion 38 of the piston member for inlet of oil to the interior of the piston.

The lower end of the piston member is counter bored at 44 with a slot 45 cut in one side of the same. The counter bore 44 receives the button head 36 of the plunger 35. The outer surface of the lower end of the piston opposite to the slot 45 is provided with a recess 46. A cotter pin 47 having one straight leg 48 and with the other leg 49 formed with an intermediate arcuate portion 50 is inserted with the straight leg 48 passing through the slot 45 in the piston for engaging under the button head 36 of the plunger 35 and with the arcuate portion 50 lying in the recess 46 on the outer surface of the piston for connecting the piston to the plunger 35.

The operation of the form of the invention illustrated in Figure 5 is as follows:

The parts are in normal position as shown in Figure 5. Pressure against the head 10 of the plunger 35 will move the plunger inwardly which moves the piston through the cylindrical portion 16 of the spout. Release of pressure against the head 10 will allow the plunger to be returned to normal position and the vacuum created in the cylindrical portion 16 will tend to retard the movement of the piston to normal position thus enabling oil to be admitted to the cylindrical portion 16 through the lateral openings 43 which passes

the ball valve 40 as the spring 41 is a weak spring for this purpose. In this manner the cylindrical portion 16 is provided with a charge of oil ready to be ejected on the next inward movement of the plunger 35. The ball valve 24 in the cage 20 and the ball valve 40 in the piston entrap the oil charge within the cylindrical portion of the spout ready to be discharged under pressure by the plunger. Inward movement of the plunger 35 will eject the charge within the cylindrical portion 16 through the spout and on release will admit another charge of oil to the cylindrical portion 16 provided the can is held with the spout downwardly so that the oil may flow through the inlets 43 in the piston.

An oil seal 33 similar to that described with reference to Figure 1 is shown as applied to the end of the spout of the can illustrated in Figure 5.

Figure 6 illustrates another modification of piston from that shown in Figures 1 and 5.

The plunger 51 of Figure 6 has a head 10 outwardly of the bottom of the can 3 while its inner end is reduced in diameter forming an extension 52 the upper end of which extension is threaded at 53. A semi-spherical valve 52 having a central aperture is mounted on the extension 52 for seating against the gasket 8 on the upper end of the sleeve 5. The piston illustrated in Figure 6 comprises a counter bored member 56 having a central aperture 57 in the lower end thereof and with the part outwardly of said aperture countersunk at 58 for serving as a valve seat in connection with the valve 54. A sleeve 59 surrounds the extension 52 within the piston 56 and is movable axially. A star wheel 60 is threaded onto the threaded end 53 of the extension 52 for allowing passage of oil past the wheel 60 on actuation of the plunger 51. A spring 61 is interposed between the underside of the star wheel 60 and the lower end of the piston so as to retain the piston in engagement with the valve 54 thus sealing the opening to the piston from the interior of the can.

Operation of the form of the invention illustrated in Figure 6 is as follows:

Inward movement of the plunger 51 moves the piston upwardly in the cylindrical portion 16 of the spout and on release of pressure against the plunger, the plunger is returned to normal position. The vacuum created in the cylinder retards movement of the piston on its return stroke so as to open passage through the piston to admit oil to the cylinder.

It will be observed that in all forms of the invention illustrated a charge of oil is entrapped in the cylindrical portion of the spout and then is forced out through the lateral openings in the cage 20 by the plunger when the plunger is actuated. This arrangement allows the discharge of oil under pres-

sure with the spout pointing upwardly as well as downwardly as delivery of the oil to the cylindrical portion of the spout is accomplished before the end of the spout is applied to the fitting into which the oil is to be ejected.

The pistons have snug fit within the cylindrical portions 16 for the purpose of preventing the passage of oil by said pistons 10 during the pressure stroke.

The pistons in the forms shown in Figures 5 and 6 move with the plungers 35 and 51 respectively, thereby eliminating springs between the cage 20 and the pistons.

- 15 The discharge of oil through the cage 20 is laterally through the side apertures 26 and not through the spring 25. This manner of discharge prevents stoppage by any dirt particles in the oil and also prevents 20 partial straining and thinning of the oil which occurs when the oil is discharged through the spring.

A gasket may be interposed between the valve 54 and the shoulder formed between the 25 extension 52 and the plunger 51 of the form shown in Figure 6.

The lower end of the spring 30 is enlarged in diameter to prevent displacement of the piston 27 when the spout is removed from 30 the can body 1.

The invention has been described more or less precisely herein, yet it is to be understood that changes may be made in the arrangement and proportion of parts and that 23 equivalents may be substituted without departing from the spirit and scope of the invention.

The invention is claimed as follows:

1. An oiler including a spout, said spout 40 having a cylindrical portion and a tapered portion, a valved passage in said spout at the junction of said portions, a piston in said cylindrical portion inwardly of said valved passage, said piston having an oil admission 45 port, a valve normally closing said port, and a plunger for moving said piston toward said valved passage to eject oil through said passage.

2. An oiler including a spout, said spout 50 having a cylindrical portion and a tapered portion, a valved passage in said spout at the junction of said portions, a piston within said cylindrical portion inwardly of said valved passage and having an oil admission 55 port, a plunger for moving said piston in a direction to discharge oil through said passage and having a valve thereon for closing said port, a spring for returning said piston to normal position, a stronger spring for returning 60 said plunger to normal position whereby said plunger is moved away from said piston as said plunger and piston are returned to normal position thereby opening said piston port to oil admission.

65 3. An oiler including a spout, said spout

having a cylindrical portion and a tapered portion, a cage in said spout at the junction of said portions, said cage containing a valve arranged to open towards the tapered portion, means in said cage for normally maintaining said valve in closed position, said cage having lateral discharge openings, a piston 70 slideable in said cylindrical portion, said piston having an oil admission port therein, a plunger for moving said piston towards said cage to discharge oil through the cage, a valve on said plunger for normally closing the piston port, and a spring for moving said piston in a direction opposite to which it is moved by said plunger.

4. An oiler including a spout, said spout having a cylindrical portion and a tapered portion, a cage in said spout at the junction of said portions, said cage containing a valve and a valve seat, said valve arranged to open towards the tapered portion, means in said cage for normally maintaining said valve against its seat, a piston slideable in said cylindrical portion, said piston having an oil admission port, a plunger for moving said piston towards said cage, said plunger carrying a valve for normally closing said piston port, a spring for returning said plunger to normal position, and a spring for moving said piston in the opposite direction, said plunger return spring being stronger than the piston spring whereby said plunger may be returned to normal position ahead of said piston and the valve thereon moved away from said piston port.

5. An oiler comprising a body, a spout removably associated with said body, said spout including a cylindrical portion and a tapered portion integrally formed, the walls of said spout adjacent said cylindrical portion and said tapered portion defining an inner annular shoulder, a cage pressed into said spout and against said shoulder, said cage having a valve seat therein, a ball valve within said cage and normally closed against said seat, a spring for maintaining said ball in closed position, said cage having laterally disposed oil outlets, a piston snugly fitting said cylindrical portion and movable therein, said piston having an oil admission port, a spring interposed between said cage and said piston for maintaining the piston normally away from said cage, a plunger for moving said piston towards said cage, said plunger carrying a valve for normally closing the piston port, a heavy spring for returning said plunger to normal position, the parts being arranged in such manner that on return to normal position after a discharge stroke of the plunger, the plunger and valve controlling the oil admission port in said piston are moved faster than the piston whereby said plunger carried valve is moved away from its seat.

6. An oiler including a spout, said spout

- having a cylindrical portion and a tapered portion, a cage member inserted in said spout at the junction between said tapered and cylindrical portions and having a valve seat 5 therein, a spring pressed ball valve within said cage arranged to open towards said tapered portion, a piston movable in said cylindrical portion, said piston having an oil admission port, a valve for normally closing 10 said port, a plunger for moving said piston toward said cage to discharge oil from said cylindrical portion past said ball valve, and spring means for moving said piston port valve away from its seat on the return stroke 15 of said piston.
7. An oiler including a spout, said spout having a cylindrical portion and a tapered portion, a piston movable in said cylindrical portion, said piston having an oil admission 20 port therein, a valve movable with respect to said piston for normally closing said port, a spring for retaining said valve in closed position, a plunger for moving said piston in a direction to discharge oil from said tapered 25 portion, a spring for moving said plunger in the opposite direction, said piston fitting said cylindrical portion in such manner as to be frictionally retarded during its return movement whereby said plunger is returned 30 to normal position by said spring ahead of said piston thus exposing the piston port to oil admission.
8. An oiler including a spout having a cylindrical portion and a tapered portion, a cage in said spout at the junction of said portions, said cage containing a spring 35 pressed ball valve for normally closing passage into the tapered portion, said cage having lateral discharge ports, a piston slideable 40 within said cylindrical portion and having a snug fit therein, a spring between said cage and said piston for normally maintaining said piston away from said cage, said spring arranged with its end portions of greater diameter than the intermediate portion for allowing oil passage thereby when said spring is compressed, and a plunger for moving said piston toward said cage to discharge oil 45 through said cage.
- 50 9. An oiler including a can and a spout, said spout being disposed on said can against endwise relative movement with respect thereto, said spout having a cylindrical portion therein, a piston movable within said cylindrical portion, a plunger operable through the oiler bottom for moving said piston in discharge direction, a spring for moving the piston in the opposite direction, said piston having an oil passage therethrough, a valve 55 on said plunger for normally closing said passage, and a spring for moving said plunger in a direction opposite to its movement in discharge direction.
- 60 10. A lubricator including a can body and a spout, said spout having a cylindrical portion, a valved passage at the end of the cylindrical portion nearer the discharge end of the spout, a piston movable in said cylindrical portion, said piston having an oil admission port therein, and a plunger having a valve 65 thereon for normally closing said port, said plunger operable to close said port and move said piston toward said valved passage to eject oil through the same.
11. A lubricator including a can body and a spout, said spout having a cylindrical portion therein, a valved passage at the end of the cylindrical portion nearer the discharge end of the spout, a piston movable within said cylindrical portion inwardly of said passage, said piston having an oil admission port 70 therein, and a plunger, said plunger having a valve thereon for engaging the piston port, said plunger being operable to close said port and move said piston toward said valved passage to eject oil through the same.
12. A lubricator including a can body and a spout, said spout having a cylindrical portion therein, a valved passage at the end of the cylindrical portion nearer the discharge end of the spout, a piston movable in said cylindrical portion, said piston having an oil admission port, a valve normally closing 75 said port, and a plunger operable to move said piston toward said valved passage to eject oil through the passage.
13. A lubricator including a can body and a spout, said spout having a cylindrical portion therein, a valved passage at the end of the cylindrical portion nearer the discharge end of the spout, a piston movable in said cylindrical portion, said piston having an oil admission port, a valve normally closing 80 said port, a plunger operable to move said piston toward said valved passage to eject oil through the passage.
14. A lubricator including a can body and a spout, said spout having a cylindrical portion, a valved passage at the end of the cylindrical portion nearer the discharge end of the spout, a piston movable in said cylindrical portion, said piston having an oil admission port therein, and a plunger operable 85 through the bottom of the can body, said plunger having a valve thereon for normally closing the piston port, said plunger being operable to close said port and move said piston towards said valved passage to eject oil through said passage.
15. A high pressure lubricator including a can body and a spout, said spout having a restricted portion between its ends, a valved passage at the restricted portion of the spout, a piston movable within said spout inwardly 90

of said passage, said piston having an oil admission port therein, a plunger extending through the bottom of the can body and operable exteriorly thereof, said plunger having a valve thereon for engaging the piston port, said plunger being operable when moved in discharge direction to close said port and move said piston towards said valved passage to eject oil through said passage.

10 In testimony whereof I have hereunto subscribed my name at Chicago, Cook County, Illinois.

EMMET H. MORROW.
